UNITED STATES PATENT OFFICE.

WENDELIN KARL, OF BUFFALO, NEW YORK.

DESIGN FOR A CURLING-STONE.

SPECIFICATION forming part of Design No. 20,525, dated February 17, 1891.

Application filed December 22, 1890. Serial No. 375,508. Term of patent 7 years.

To all whom it may concern:

Be it known that I, WENDELIN KARL, a citizen of the United States, residing at Buffalo, in the county of Erie and State of New York, have invented a new and useful Improvement 5 in Designs for Curling-Stones, of which the following is a specification.

My design relates to the ornamentation of the circular bodies used in the game of curling and known as "curling-stones."

The accompanying drawing is a perspective view of a curling-stone embodying my novel design.

The design consists, essentially, of a series

of horizontal ribs or corrugations *a*, encircling 15 the body of the stone and extending from its base *b* to its crown *c*, thereby producing a corrugated surface, which gives the stone a pleasing appearance.

I claim—

The design for a curling-stone herein shown and described.

Witness my hand this 19th day of November, 1890.

WENDELIN KARL.
